UNITED STATES PATENT OFFICE.

CHARLES LONGSTRETH, OF YEADON, AND CHARLES W. G. KING, OF PHILADELPHIA, PENNSYLVANIA, ASSIGNORS TO THE UNITED STATES METALLIC PACKING COMPANY, OF PHILADELPHIA, PENNSYLVANIA, A CORPORATION OF PENNSYLVANIA.

METALLIC PACKING FOR PISTON-RODS.

SPECIFICATION forming part of Letters Patent No. 694,764, dated March 4, 1902

Application filed September 17, 1900. Serial No. 30,261. (No model.)

To all whom it may concern:

Be it known that we, CHARLES LONGSTRETH, of Yeadon borough, Delaware county, and CHARLES W. G. KING, of Philadelphia, State of Pennsylvania, have invented certain Improvements in Metallic Packing for Piston-Rods, &c., of which the following is a specification.

The object of our invention is to provide for the secure confinement together of the segments of a sectional casing for containing metallic packing for piston-rods, valve-rods, &c., without unduly increasing the diameter of said casing, an object which we attain in the manner hereinafter set forth, reference being had to the accompanying drawings, in which—

Figure 1 is a longitudinal section of part of a cylinder, piston-rod, stuffing-box, and rod-packing constructed in accordance with our invention; and Fig. 2 is a perspective view of the parts of one of the sectional packing-ring casings detached from each other.

In Fig. 1 part of the stuffing-box casing of an engine-cylinder is represented at 1, part of the piston-rod at 2, and the stuffing-box cap or follower at 3, all of which parts may be similar to those of ordinary engines, except that the cap or follower 3 has a seat for a ball-joint ring 4 and a recess for the reception of a flange of the sleeve 5, which enters the outer end of the stuffing-box casing and is confined thereto by said cap or follower. In the present instance the rod is provided with two sets of packing-rings, each set of rings being contained in a sectional casing comprising segments 6, recessed for the reception of the packing-rings 7, the casing being constructed in sectional form in order that it may be fitted to the rod, which in many cases has at its outer end shoulders or projections of such diameter as would preclude the slipping of an annular casing of the required diameter longitudinally onto the rod.

In order to secure together the segments 6 of the packing-ring casing, we form in the opposite faces of said segments beveled grooves 8 for the reception of beveled ribs 9 upon seg-

ments 10, which are secured to the segments 6 by screws or other equivalent fastenings 11, 50 the joints between the segments 10 being at right angles to those between the segments 6, whereby the two sets of segments mutually retain each other in position, a clamping or wedging effect being due to the action of the 55 beveled inner faces of the ribs 9 upon the correspondingly-beveled inner faces of the grooves 8, the outer faces of said ribs and grooves being preferably free from contact with each other, as shown in Fig. 1. The segments 6 are thus held together without the aid of any encircling ring, although, if desired, such an encircling ring may be used as an additional protection and in some cases the securing-segments 10 may be used only 65 at one end of the packing-ring casing instead of at both ends of the same.

Pressure is exerted upon the outer packing-rings 7 by means of a follower 12, upon which bears a ring 13, acted upon by springs 70 14, contained in sockets in said ring and bearing against a ring 15, which is seated against an internally-projecting flange 16 of the sleeve 5, all of the rings 12, 13, and 15 being composed of sections to permit of their being 75 readily fitted to the rod. The inner end of the sleeve 5 has a seat for the ball-joint ring 17 of the inner packing-ring structure which is precisely similar to the outer packing-ring structure with the exception that the follower 80 12^a is elongated and has a flanged inner end socketed for the reception of springs 18, which bear against the shoulder at the inner end of the stuffing-box casing.

Having thus described our invention, we 85 claim and desire to secure by Letters Patent—

1. The combination in a metallic-rod packing, of a packing-ring casing composed of segments, with retaining-segments secured 90 at each end thereof to the face of said segments of the casing and disposed so as to break joints with said casing-segments, substantially as specified.

2. The combination in a metallic-rod pack- 95 ing, of a packing-ring casing composed of

segments, with retaining-segments secured at each end thereof to the face of said segments of the casing and having ribs adapted to grooves therein, said retaining-segments being disposed so as to break joints with the casing-segments, substantially as specified.

3. The combination in a metallic-rod packing, of a packing-ring casing composed of segments, with retaining-segments secured at 10 each end thereof to the face of said segments of the casing and having beveled ribs engaging with correspondingly-beveled grooves in the casing-segments, said retaining-segments being disposed so as to break joints with the casing-segments, substantially as specified.

4. The combination in a metallic-rod packing, of inner and outer sets of packing-rings each having a spring-pressed follower, with 15 an interposed sleeve having a flange upon 20 which is seated a ring constituting a bearing

for the springs which act upon the follower of the outer set of packing-rings, substantially as specified.

5. The combination in metallic-rod packing, of inner and outer sets of packing-rings 25 each having a spring-pressed follower, with the interposed sleeve having a seat for a ball-bearing ring forming part of the inner packing structure, and an internal shoulder upon which is seated a ring which constitutes a 30 bearing for the follower-springs of the outer packing, substantially as specified.

In testimony whereof we have signed our names to this specification in the presence of two subscribing witnesses.

CHARLES LONGSTRETH.

CHARLES W. G. KING.
